UNITED STATES PATENT OFFICE.

WILLIAM A. JAMESON, OF NIAGARA FALLS, NEW YORK.

DESIGN FOR A LADLE OR SIMILAR ARTICLE.

SPECIFICATION forming part of Design No. 30,648, dated May 2, 1899.

Application filed March 24, 1899. Serial No. 710,372. Term of patent 7 years.

To all whom it may concern:

Be it known that I, WILLIAM A. JAMESON, a citizen of the United States, residing at Niagara Falls, in the county of Niagara and State 5 of New York, have invented and produced a new and original Design for a Ladle or Similar Article, of which the following is a specification, reference being had to the accompanying drawings, forming part thereof.

10 The leading and essential features of my design consist in the peculiar configuration or shape of the bowl and the ornamentation of the interior and exterior surfaces thereof, especially the interior surface, which has oppositely-disposed concave lips, with an intermediate lip disposed opposite the point where the handle is attached to the bowl, and fluted scrolls between the lips.

Figure 1 is a plan view of the interior surface of the bowl, with a handle shown in dotted lines; Fig. 2, a vertical longitudinal section of the bowl, and Fig. 3 a transverse section of the same.

In the drawings I have shown a ladle the 25 bowl *a* of which represents my new design, the handle being shown in dotted lines.

The outline of the upper edge of the bowl is approximately oval in shape, and each end is formed with a concave lip *c* and the front

30 with a rounded lip *d*. Between the respective concave lips and the front lip is a series of fluted scrolls *e*, which extend down into the bowl and have their heads slightly curved outwardly and downwardly. The outer edge of the front lip *d* is formed with a bead *f*, 35 which has its ends terminating in scrolls *g*. At each side of the point where the handle is attached the upper edge curves downwardly and upwardly, and between this curve and each concave lip is a series of fluted scrolls *h*, 40 similar to the scrolls *e*.

On the exterior surface of the bowl the outline of the upper edge and the ornamentation is very generally preserved, except that those parts which are convex on the interior surface are concave on the exterior surface and those parts that are concave on said interior surface are convex on said exterior surface. 45

What I claim is—

The design for a ladle, or similar article, as 50 shown and described.

In testimony whereof I affix my signature in the presence of two witnesses.

WILLIAM A. JAMESON.
